THERAPEUTIC APPLICATOR EMPLOYING
VAPOR PASSED THROUGH A BEAM OF
RADIANT ENERGYFrank R. Hart and Sally W. Lasher, Pacific
Grove, Calif.Application December 23, 1931
Serial No. 582,830

2 Claims. (Cl. 174—87)

This invention relates to therapeutic applicators employing vapor passed through a beam of radiant energy, and is an improvement on our copending application filed November 13, 1931, 5 for Improvements in ultraviolet ray steam inhalers, Serial No. 574,896.

The applicators of this invention provide means to pass vapor through a beam of ultraviolet light, or other suitable energy, and deposit such vapor 10 in the body, either by inhalation or by projection.

For the purpose of this specification, vapor that has been passed through a beam of radiant energy may be referred to as having been "Ray- 15 ized."

15 We do not attempt to explain what takes place when vapor is rayized in the manner indicated, but in our practice of this invention we have proved that patients suffering from affections of the respiratory tracts, colds etc. are greatly bene- 20 fited by a few treatments.

The vapor we have used is ordinary steam without medication but which has been rayized. We believe that vapor produced by a conventional atomizer, when sprayed through a beam of ultra- 25 violet light would have the same effect; and we assume that the well known lethal effect of these rays on micro-organisms is in some way taken on by the vapor when rayized.

Our inhaler applicators deposit the rayized va- 30 por by natural inspiration.

For treatment of the urethra, the rectum, and the vagina, the present application discloses means whereby rayized vapor can be introduced to such parts under pressure, it could also be 35 sprayed on the gums to treat pyorrhea and variously applied for other therapeutic purposes.

At present ultraviolet ray machines represent an outlay of several hundred dollars; therefore in order not to monopolize one whole machine 40 while treating one patient we disclose a device whereby multiple treatment may be had simultaneously.

The objects of our invention comprise the following desiderata:—

45 To provide a novel bezel for the lens of an ultraviolet ray machine or lamp, said bezel besides forming means to retain the lens of the lamp in position, carries means wherewith to engage an applicatory device having complementary means to afford a water-tight joint between the bezel 50 and the device.

To provide novel means to introduce vapor into cavities of the body under pressure.

To provide an applicator with novel means to 55 reduce the heat given off by some forms of ultraviolet ray machines or lamps.

To provide a novel device associated with a source of steam and having a relief check valve and a port arranged to admit a regulable influx of air to cool the steam before its dispensation. 60

To provide a sump arranged to catch the water of condensation which accumulates during treatment, and a drain cock to relieve the sump at suitable intervals.

To provide a novel mouth-and-nose inhaling 65 element.

To provide a device arranged to treat several patients at the same time; together with further objects and advantages hereinafter appearing, particularly pointed out in the claims and illustrated in the accompanying drawings attached hereto and made part hereof, in which:—

Figure 1 is a diagrammatic elevational view showing the general arrangement of our invention in one embodiment. 75

Figure 2 is a side elevational view of our invention as attached to an ultraviolet ray lamp or machine, the steam kettle not shown.

Figure 3 is a front elevational view of an applicator of the present invention with parts cut 80 away.

Figure 4 is a section taken on the line IV—IV of Figure 2.

Figure 5 shows another embodiment of the device taken on the line of V—V of Figure 3. 85

Figure 6 is a section taken on the line VI—VI of Figure 5.

Figure 7 is a front elevational view of the bezel element.

Figure 8 is a section taken on the line VIII—VIII of Figure 10. 90

Figure 9 is a side elevational view of the ultraviolet ray lamp with the inhaler attached and carrying the mouth and nose applicator.

Figure 10 is a front elevational view of the inhaler showing the steam kettle in reduced proportion and attached thereto. 95

Figure 11 shows the inhaler carrying an atomizer cooperative therewith.

Figure 12 is a mid-longitudinal sectional view 100 showing the lower half of a pressure applicator carrying a vaginal tip.

Figure 13 is a top plan view of a device having multiple inhaler elements.

Figure 14 is a section taken on the line XIV— 105 XIV of Figure 13.

Figure 15 is a section taken on the line XV—XV of Figure 16.

Figure 16 is a front elevational view of the mouth and nose applicatory element and 110

Figure 17 is a longitudinal sectional view of the check valve set into the vapor pipe.

Similar reference indicia refer to similar parts throughout the several views:—

Referring particularly to the drawings:—

Figure 1 shows the steam kettle K connected 5 with the applicator drum B by the vapor pipe 5.

The cooling valve C is provided in said pipe adjacent the outlet of the kettle K and comprises the axially displaceable sleeve 6 a slidable fit on the pipe 5 between the collars 7—7 which are 10 suitably spaced apart to expose the port 8 and admit air in regulable quantities to said vapor line sufficiently to cool the vapor to a degree agreeable to the patient; said sleeve being adjustable by the patient through manual operation of the button 9, all well shown in Figure 10.

The check valve 10 is interposed between the valve C and the drum B, and is arranged to relieve steam pressure in the kettle and to serve another purpose later appearing.

20 The applicator element comprises the cylindrical drum B, provided at the forward end thereof with means for removably attaching thereto an applicatory instrument, which means may well be nipple 11.

25 The rear wall 12 of said drum is apertured at 13 to admit the radiant light from the lamp A to shine into the drum and is provided with the hook 14 adapted to engage the complementary aperture 15 of the bezel 16; and, further provided 30 with the swinging latch-bolt 17 adapted to engage the slot 18 of the bezel and be locked by the nut 19, when so engaged and furnished with the rubber gasket 20 centered on the annular shoulder 21 said parts constitute a water-tight joint between 35 said light and said drum, with ability for radiant light, such as ultraviolet rays, to flood the interior of the drum. It being understood that the lamp lens 22, well shown in Figure 4, forms a portion of the rear wall of said drum.

40 The drum B may be formed with a single outer shell 23 as shown in Figures 12 and 14, or may be provided with the inner tubular wall member 24 to form the annular space for circulation of a cooling medium as shown in Figure 5, a form 45 adaptable for use with lamps of the Kromayer type which emit a pre-cooled light.

For lamps which emit uncooled radiant light the cooling medium has to pass through the ray beam in order to cool the rays. To accomplish 50 this the rear end of the member 24 is severed from the rear wall 12 and the lens 25 is provided to supply a ray-permeable closure for the cooling area.

55 The pipes 26 and 27 are the respective inlets and outlets for the circulation of cooling medium, which ordinarily is water from a suitable source and arranged to waste into a sewer or an appropriate waste receptacle.

60 The pipe 5 leads the vapor completely into the light beam where it becomes rayized or saturated by the radiant energy.

The drain 28 conducts the condensed steam into the sump 29 provided with the drain-cock 30.

65 The pressure bulb 31 is in open communication with the pipe 5. Obviously, when the cock 30 is closed pressure upon the bulb 31 will close the check 10 and vapor contained within the applicator will be forcibly expelled through any hollow applicatory instrument which may be attached to the nipple 11.

70 The instrument 32 Figure 2 is adapted to administer vapor to the urethra; the instrument 33 is suitable for the rectum, and the instrument 34 is for the vagina.

With each relaxation of pressure the bulb 31 resumes its normal shape and in doing so opens the check 10 and sucks in another charge of vapor which immediately becomes rayized and is ready to be discharged into the organ.

80 As shown in Figure 9 the drum B is arranged for inhaling the rayized vapor in which case the pressure bulb 31 is not needed, and the mouth and nose element D is substituted for said applicatory instruments. Said element may be attached to the drum B direct as shown in said figure, or it may be attached by a hose 35 as shown in Figures 13 and 16.

85 The element D comprises the mouth-piece 36, the bi-furcated nostril members 37—37, the outwardly-operative check 38 and the exhaust element 39 by means of which the vapor may be expelled.

90 Figure 13 shows a relatively larger drum having a plurality of outlets 35 which may be either flexible hose or pipes, each provided with an element D.

95 In Figure 11 we show our inhaler device carrying an atomizer element E, adapted and arranged to convey vapor into the ray beam from the vessel 100 40 through the pipe 5' into the drum B.

100 It should be noted that the nipple 11 is tapered outwardly and that the respective applicatory instruments have the tapering walls 41 and are bored taper at the large end to fit over said taper 105 of said nipple.

105 It should be explained that the bulb 31 is only needed when rayized vapor is to be forced into non-respiratory cavities, in which case pressure upon said bulb expels the rayized vapor from the 110 instrument, the check 10' being closed. Release of the bulb draws in a fresh charge of mixed air and vapor through the pipe 5, by opening the check 10' normally closed against the seat 10, the valve element C being adjusted to admit the required influx of air, which completes the cycle.

115 It is believed that our invention and the advantages to be derived from it are fully explained. In reducing the invention to practice, certain minor features in construction, combination and arrangement of parts may necessitate alteration to which the patentees are entitled, providing such alteration is comprehended in the scope of what is claimed.

120 What we claim is:—

125 1. In an apparatus of the kind described having a source of radiant energy and a source of vapor, a receptacle in the radiant path, and a conduit to convey vapor from said source to said receptacle; a check valve in said conduit adapted to open outwardly from the vapor source and a manually operable bulbous element in communication with the conduit to create pressure to close said check valve and simultaneously expel said vapor from the receptacle via an applicatory instrument.

130 2. In apparatus of the kind described, having a source of radiant energy and a source of heated vapor, a receptacle for the vapor comprising a drum disposed in the radiant path; means to circulate a cooling medium in the drum, a hollow inner member carried by the forward end of said drum and extending backwardly toward the rear end thereof, a ray-permeable lens mounted concentric with the rays in the rear end of said member, said lens adapted to exclude said cooling medium from said member and permit it to cross

135 the rays.

140 3. In apparatus of the kind described, having a source of radiant energy and a source of heated vapor, a receptacle for the vapor comprising a drum disposed in the radiant path; means to circulate a cooling medium in the drum, a hollow inner member carried by the forward end of said drum and extending backwardly toward the rear end thereof, a ray-permeable lens mounted concentric with the rays in the rear end of said member, said lens adapted to exclude said cooling medium from said member and permit it to cross the rays.
